UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

EXCAVATING-BUCKET.

1,346,999.

Specification of Letters Patent. Patented July 20, 1920.

Application filed October 19, 1918. Serial No. 258,843.

To all whom it may concern:

Be it known that I, WILLIAM M. VENABLE, a citizen of the United States, residing at Pittsburgh, in the county of Allegheny and State of Pennsylvania, have invented certain new and useful Improvements in Excavating-Buckets, of which the following is a specification.

My invention relates to improvements in excavating buckets; and has for its primary objects to improve the construction and increase the efficiency, utility and durability of apparatus of this type; the provision of a bucket head structure in which is combined the characteristics of maximum rigidity and cheapness in its construction, and wherein guards are provided for the bucket lines so that the latter cannot become displaced or grind against the head when the bucket is not hanging perpendicularly, or turns over on its side; and to provide an improved stop bar device arranged with reference to the sheave or main pin of the head. The invention also contemplates certain novel details of construction, combination and arrangement of the improved apparatus, whereby certain important advantages are attained, as will be more fully described hereinafter, and pointed out in the claims.

These, together with such other objects and advantages as are incident to my invention, I attain by means of a construction illustrated in preferred form in the accompanying drawings, wherein—

Figures 1 and 2 are respectively side and rear elevations of a bucket embodying the improvements;

Fig. 3 represents a side elevation of the improved bucket in its open position;

Figs. 4, 5 and 6 are enlarged detailed views of the main lever arm and its sheave casing;

Fig. 7 represents a slightly enlarged view in rear elevation of the head and upper portions of the corner bars of the bucket;

Fig. 8 is a vertical section view of the head taken along the lines VII—VIII of Fig. 7; and

Fig. 9 is a top plan view of the head in Fig. 7.

Referring to the drawings, the reference numerals 10, 10, denote a pair of clam-shell scoops hingedly connected together by the

hinge pin 11. They are supported from the head block A by two pairs of corner bars 12, 12, and 13, 13, which are pivoted at their lower ends to the outer corners of the scoops by the corner pins 14, 15. The upper end portions of corner bars 12 are riveted to the head plates 17 of the head block A, as indicated at 16, and extending centrally through these plates and the upper hubbed ends of both pairs of corner bars 12, 13, is a single head pin 18, which latter also rotatively carries between the plates the large head sheave 19 and the small head sheave 20. Disposed about the major portion of the sheaves 19 and 20 is a segmental distance member 22 made of plate and secured by means of the clamping elements 21 to the plates 17. Utilizing such a construction at this point, as I do, serves to provide a very rigid and compact head block structure, and one that furthermore materially reduces the number of hoisting sheave bearings ordinarily required in buckets of this type to the single head pin shown.

The reference numeral 23 designates a rope collar for the hold line 24, and 25 and 26 respectively denote a guide sheave and a 80 guide roller for the hoisting line 27, the members 23 and 26 being mounted upon the hold line pin 28, and the member 25 upon guide sheave pin 29 in such a manner as to receive between its side plates 27' the central flange 26' of the guide roller, and thereby hold the hoist line against slippage and prevent frictional contact thereof with any rigid head part should the bucket be canted.

These members and their pins are preferably positioned intermediate the upper portions of the head plates 17, as shown in Figs. 7, 8 and 9, and above the open top of the segmental member 22, and through which opening the hoist line extends upwardly from the small head sheave 20 toward and through the pass 30 formed by the anti-friction members 25 and 26.

This segmental plate member has its wall peripherally formed with slots 31 and 32 100 for the passage of the hoist line to the sheave 40 of the lever arm B, which is in the bight of the line, and is provided with other slots, 33 and 34, the line passing through the former slot 33 after leaving the 105 large head sheave 19', and has its end termi-

nally secured at 35 to the short arm 36 of a bell crank lever, the long arm of which is indicated by the reference numeral 37. This lever is pivotally mounted on the bucket 5 hinge pin 11, and at its free end is provided with a stop bar comprising the pivotally connected short and long links, 38, 39, respectively, said stop bar pivoted terminally at 41 to the lever arm 37 and at its upper 10 and other end to the head pin 18 after passing through the slot 34 of the head block (Fig. 7). These slots are elongated sufficiently to permit the free working of the hoist line and stop bar between the closed 15 position of the bucket (Fig. 1) and its open position (Fig. 3); the stop bar construction serving to effectually brake the bucket scoops as they approach their full open positions, and particularly so in view of the 20 fact that it is centrally pivoted on the head pin, thus providing a well-balanced, durable and dependable structure.

Referring now more particularly to Figs. 2, 4, 5 and 6, it will be seen that the main 25 lever B consists of a pair of spaced arm members 42 provided with hubs 43 pinned or otherwise secured to the hinge pin 11 intermediate the pairs of corner bars, and having extensions 42' secured centrally to 30 the back of one of the scoops. At the upper or outer end of these members 42 is a sectional casing for the sheave 40, the lower casing section 44 being formed integrally with said members, while the upper casing 35 section 45 is detachably connected with section 44 by suitable securing elements 46 which pass through corresponding lugs 47 provided on said sections. The sheave 40 is housed within this casing and is carried on 40 a sheave pin 48 which passes through the line of separation between the sections and is mounted for rotation in the upper ends of the arms 42. It will be noted that the casing is slotted peripherally with upper and lower 45 elongated slots 49, 50 (Fig. 5) for the free passage of the hoist line 27 during movement of the main lever B on the hinge pin 11, and also that it is crooked or bent in the manner shown in Figs. 2 and 4, so as to 50 bring the sheave 40 in the requisite and proper plane and thereby give straight line leads from the sheaves in the head block A. This is one of the advantageous features of 55 my invention, and which, with the head block construction described, operates to confer longevity upon the line and effects an increase in the efficiency and durability of the bucket. Furthermore, a noteworthy measure of protection is afforded to the lever 60 arm sheave by reason of its being housed in the casing, and should any small particles of material work through the narrow slots, 49, 50, a drain opening 51 is provided in the basal portion of housing section 44 for their 65 discharge when the lever arm is in move-

ment toward its raised or closed position. As the sheave turns during this movement it tends to scour out any particles that may have collected in the casing, and which are thereby forced out through the drain opening 51 in the direction indicated by the arrow in Fig. 5. In other words, I provide a self-clearing protective covering for the lever arm sheave, and one which is especially efficacious where the bucket is working 70 under water. This represents another important feature of the invention.

As will be seen from an inspection of the drawings, the bell-crank or auxiliary lever arm is mounted to oscillate on the hinge pin 80 11 in the space between the arms 42 of the main closing lever, and the hoist or closing cable 27 extends from the arm 36 over the large head sheave 19 to the lever arm sheave 40, and from thence under the small head sheave 20 upwardly past the anti-friction guard members 25 and 26. When the bucket is in its open position a pull exerted on the line will close the scoops, and with the hold line held taut a slackening of the closing 90 line will permit the opening of the scoops. In order to prevent the slackened line from slipping off the small head sheave 20, I provide a stud 52 in juxtaposition therewith and whose ends are carried in the plates 17. 95

During the opening movement of the scoops, the bell-crank or auxiliary lever and stop bar act together as a shock-absorber, as I have previously indicated, the lever turning on the hinge pin until the stop bar assumes the vertical position shown in Fig. 3. The result is that the arm 36 describes a short arc at an accelerated rate of speed as compared with that of the main lever B, and the opening movement of the scoops is gradually checked through the closing cable, the articulation of the stop bar being such as to minimize strain on bucket parts during this movement. Moreover, the auxiliary lever and stop bar coöperate with the closing or 100 main lever in the closing operation of the bucket and thereby attain the maximum closing effect from the pull in the closing cable in a very facile manner, the stop bar assuming its various operative positions during bucket actuation without any interference whatever with any other moving part of the bucket. And it will be obvious, from the foregoing description, that the line not only has straight leads between sheaves, but 105 is, moreover, guided against and guarded from frictional contact with fixed parts, and as so guided and guarded it is held against slippage or any tendency whatever to jump off the sheaves about which it is reeved. The 110 entire construction is simple, strong and efficient, and these characteristics are particularly present in the head block wherein the main head pin 18, upon which the head sheaves and stop bar turn, passes through 115 120 125 130

those corner bars 12 which at one side of the bucket are firmly riveted to the head plates and turns in those bars. It is pinned at 53 to the other pair of corner bars 13, so that 5 the latter with the head pin provide a like measure of rigidity at the other side of the bucket.

What I claim is:

1. In a bucket, the combination of a pair 10 of pivoted scoops provided with a pair of corner bars at each side of the bucket, and a head block comprising side plates rigidly secured to one pair of said corner bars, and a pivot pin extending through said 15 plates to receive the ends of both pairs of corner bars, said pin being rigidly connected with the ends of the other pair of corner bars and adapted to turn in the ends of the first mentioned pair of corner bars.

2. In a bucket, the combination of a pair 20 of pivoted scoops provided with a pair of corner bars at each side of the bucket, and a head block comprising side plates rigidly secured to one pair of said corner bars, a 25 pivot pin extending through said plates to receive the ends of both pairs of corner bars, said pin being rigidly connected with the ends of the other pair of corner bars and adapted to turn in the ends of the first mentioned pair of corner bars, sheaves on said 30 pivot pin, and a housing for said sheaves mounted intermediately of and on said side plates.

3. In a bucket, the combination of a pair 35 of pivoted scoops provided with a pair of corner bars at each side of the bucket, and a head block comprising side plates rigidly secured to one pair of said corner bars, a pivot pin extending through said plates to 40 receive the ends of both pairs of corner bars, said pin being rigidly connected with the ends of the other pair of corner bars and adapted to turn in the ends of the first mentioned pair of corner bars, sheaves on said 45 pivot pin, a housing for said sheaves mounted intermediately of and on said side plates, and a hoisting lever for the scoops having a hoist line reeved about said sheaves, said housing being slotted to permit the passage 50 of the line during opening and closing movement of the bucket.

4. In a bucket, the combination of a head 55 block, a pivot pin in said block, a pair of pivoted scoops, an auxiliary lever mounted on the scoop pivot, and a stop bar attached at one end to the auxiliary lever and at the other end to the pivot pin in the block.

5. In a bucket, the combination of a pair 60 of pivoted scoops provided with supporting corner members, bucket closing means including a closing line and a pair of sheave members, an auxiliary lever provided with a stop bar member, and a bucket head for the scoops comprising a block provided with a head pin common to and positioned to

receive all of said members, part of said members rigidly secured to said pin and another part thereof adapted to turn on said pin.

6. In a bucket, the combination of a pair 70 of pivoted scoops provided with supporting corner members, bucket closing means including a closing line and a pair of sheave members, an auxiliary lever provided with a stop bar member, and a bucket head for the scoops comprising a block provided with a head pin common to and positioned to 75 receive all of said members, part of said members rigidly secured to said pin and another part thereof adapted to turn on said pin, said block including a housing disposed about said head pin and provided with openings for the closing line and said stop bar member.

7. In an excavating bucket, the combination 80 of a pair of pivoted scoops provided with a hinge element and supporting corner members, a head block for said members, bucket closing means including a main closing lever and a closing line running through said block, an auxiliary lever mounted on 85 said hinge element and having a stop bar member, said block including a head pin common to said members and a housing provided with slotted openings for the passage of the closing line and said stop bar, 90 part of said members rigidly secured to said pin and another part thereof adapted to turn on said pin, and said auxiliary lever terminally connected with said closing line.

8. In a bucket, the combination of a head 95 block, a pivot pin in said block, a pair of pivoted scoops, a bell crank lever mounted on the scoop pivot, and a stop bar attached at one end to the bell crank lever and at the other end to the pivot pin in the block. 100

9. In combination, a bucket closing lever arm provided with a sheave housing and a sheave rotatively mounted therein, the lower wall of said housing below said sheave apertured to provide a discharge passage for 110 the discharge of foreign matter forced theretoward by said sheave.

10. In combination, a bucket closing lever arm provided with a sheave and a two-part housing for said sheave, a line reeved on 115 said sheave, one part of said housing formed integrally with the arm and the other part being detachable, and a pivot pin having end bearings in both parts, said housing peripherally slotted for the passage of the 120 line therethrough.

11. In combination, a bucket closing lever arm provided with a sheave and a two-part housing for said sheave, a line reeved on 125 said sheave, one part of said housing formed integrally with the arm and the other part being detachable, and a pivot pin having end bearings in both parts, said housing peripherally slotted for the passage of the line therethrough, and said inter- 130

gral housing part formed with a basal drainage opening below said sheave adapted to drain when the bucket is closed and serving to protect the under side of the sheave when the bucket is open.

12. In a bucket, the combination of a head block, a main pivot pin in the block, operating sheaves on the pin, an operating cable reeved on said sheaves, and a guide sheave and a guide roller for the cable pivoted on separate pins in the head block above the main pivot pin, the guide sheave and the guide roller arranged so that the guide sheave receives the roller between its side plates.

13. In a bucket, the combination of a pair of pivoted scoops provided with a pair of

corner bars at each side of the bucket, and a head block rigidly secured to one pair of said corner bars, and a pivot pin in the head block adapted to receive the ends of both pairs of corner bars, said pin being rigidly connected with the other pair of corner bars.

14. In a bucket, the combination of a pair of pivoted scoops, a head block, a pivot pin in the head block, a pair of corner bars for one scoop rigidly secured to the head block to form a rigid supporting frame for its scoop, and a pair of corner bars for the other scoop rigidly secured to the pivot pin to form a rigid supporting frame for its scoop, the frame including the head block pivoting on the frame including the pin.

WILLIAM M. VENABLE.
